UNITED STATES PATENT OFFICE

2,451,680

ELECTRIC LIGHT SOCKET

Herbert Lagin, New York, N. Y.

Application December 15, 1945, Serial No. 635,186

5 Claims. (Cl. 200—51.16)

1

The present invention relates to electric light sockets and more particularly to the type used in the assembly of electric lamps and light fixtures of all types.

In my co-pending application Ser. No. 618,864, filed September 27, 1945, for Electric light socket, now Patent No. 2,427,464, issued September 6, 1947, I have described and illustrated a socket of the same general type but in which the housing comprises three separate parts and in which no provision is made to hold the prongs against inadvertent removal.

The present invention contemplates in general a safety socket of the same general type and having the same general objects as is disclosed in my said co-pending application but in which the socket housing comprises only two parts, a sleeve and a cap member therefor, that interfit.

The present invention further contemplates a socket having prongs which are formed so as to hold the electric wires together in proper operative association and which prongs are so constructed that they cooperate with the housing so that they are caught thereby to prevent the inadvertent separation of the cap from the sleeve.

The present invention still further contemplates the provision of a push-pull switch that cooperates with the prongs in a novel manner.

The present invention still further contemplates the provision of such a socket adapted for use with a switch by means of which any one of three selected light intensities, for example, 50 watts, 100 watts and 150 watts, may be utilized.

These, other and further objects and advantages of the present invention will be clear from the description which follows and the drawings appended thereto in which

Fig. 1 is a top plan view of a socket embodying my invention;

Fig. 2 is a partial elevation thereof;

Fig. 3 is a section on the line 3—3 of Fig. 1;

Fig. 4 is a section on the line 4—4 of Fig. 2;

Fig. 5 is a partial section on the line 5—5 of Fig. 4;

Fig. 6 is a section on the line 6—6 of Fig. 3;

Fig. 7 is a sectional elevation of a modified form of my electric socket;

Fig. 8 is a section on the line 8—8 of Fig. 7;

Fig. 9 is a detail view of the snap on and off switch illustrated in Fig. 7;

Fig. 10 is a sectional elevation of a further modified form of my electric socket;

Fig. 11 is a section on the line 11—11 of Fig. 10;

Fig. 12 is a side view of one of the parts com-

prising the switch means of the modification illustrated in Fig. 10.

Throughout the different figures illustrating various modifications of my invention I have used the same reference characters to indicate like elements of construction for each modification.

Referring now to the drawing and more particularly to Figs. 1 to 6 inclusive, the lamp socket 10, according to the present invention, essentially comprises the cap 12 and the sleeve 14, which are each preferably made from a heat resisting thermosetting plastic which is an electrical insulator and which may be cast or molded therefrom or formed by well known conventional methods.

The skirt 14, which is internally threaded at 16 to receive therein a conventional bulb or lamp (the upper metallic base 17 of which is indicated by broken lines), tightly fits and is frictionally held in the recess 18 of the cap 12, which latter is provided with the internally threaded opening 20 through which the light cable 21 extends.

The opening 20 is threaded to receive, if desired a conventional cable protecting union (not illustrated) in the collar 22.

Secured to the interior of the skirt 14, as by the rivets or screws 24, I provide the insulating washer 26 which fits into a corresponding recess formed by the shoulders 28 in the interior of the skirt 14 and which washer separates the switch mechanism compartment 30 from the lamp receiving compartment 32.

Extending down from the underside of the cap 12 and secured thereto as by the screws 34 and 36, the heads of which are positioned in the recess 18 above the top of the skirt 14, I provide wire retaining prongs which are formed from a resilient electric conducting material, bent over upon itself to form the spaced elements 38 and

40 42 and 44.

To assemble the cap 12 on the skirt 14, the cable 21 is inserted in the opening 23 and one wire 46 thereof slipped into the space between the prong elements 38 and 40 and the other wire

48 thereof inserted in the space between the elements 42 and 44. The prong elements are thus forced apart by the wire, which is held therebetween by the tension of the prong elements. The skirt 14 is forced into the recess 18 of the cap 12, the collar 50 being resiliently thereby pressed slightly outward, the prongs with the wire held therebetween entering the skirt through the corresponding openings 52 and 54 in the top wall 56 of the skirt.

55 The elements 38 and 40 are thus pressed against

the wire 46 and the elements 42 and 44 against the wire 48 by the channel walls formed in the skirt so that the wires cannot be loosened and separated from contact with the prongs.

In order to catch the prongs so that they cannot be removed and the cap 12 inadvertently separated from the skirt 14, I punch out from the prong element 38, the locking catch member 58 and from the prong element 44, the locking catch member 60.

Since the prongs are formed from a sufficiently resilient material, these locking catch members will be forced inward by the walls 62 and 64 to spring under the shoulders 66 and 68 when they pass them upon forcing the skirt 14 into the cap 12. Thus, a locking means is provided which prevents inadvertent separation of the housing members.

There is thus provided a very simple means for securing the wires in operative contact with the prongs and the components of the socket together that lends itself peculiarly to production methods of assembly since it eliminates screws or soldering but yet provides a socket, the parts of which cannot ordinarily be separated.

The prong member which is comprised of the elements 38 and 40 is shorter than the prong member which is comprised of the elements 42 and 44 and will be disposed above the washer 26 in the compartment 30 when the cap and sleeve are assembled as previously described.

The prong 42 and 44 is of such length that it will extend into the chamber 32 so that it will be contacted by the outer part of the metallic base 18 of the lamp when it is screwed into the socket. An elongated opening 70 is provided in the washer 26 to permit the end of the longer prong to pass into the chamber 32.

The center of the washer 26 has riveted thereto the terminal 72 which is positioned on the underside of the washer to form a contact with the central terminal on the lamp base 18. Secured to the washer on the upper side thereof, I provide the resilient electric conducting switch member 74, the resilient arm 76 of which is normally tensioned out of contact with the prong element 40 as illustrated by the unbroken lines of Fig. 3.

In order to provide means for opening and closing the lamp circuit which is made through the wire 46, the prong element 40, the resilient arm 76, the terminal 72, the lamp, prong element 44 and wire 48, I arrange in the recess 78 which communicates with the opening 54, the shaft 80 which is journaled in the walls 82 and 84 of Fig. 3.

On one end of the shaft 80, on the exterior of the skirt 14, I mount the knob or button 86, which therefore constitutes a switch handle and which is knurled to readily turn the switch handle and intermediate the journal walls 82 and 84, I secure the switch closing member 88, which latter engages the resilient arm 76 to force it into contact with the prong element 40 and thus close the circuit through the lamp, as illustrated by the broken lines of Fig. 3.

Upon bringing the member 88 out of engagement with the resilient arm 76, the latter resiliently springs away from the prong element 40 to open the switch.

The shaft 80, the walls 82 and 84, the knob or button 86 and the switch closing member 88 are all formed from an electric non-conducting material.

In order to permit separation of the cap 12 from the skirt 14, which are held together against

separation, as described by the locking catches 58 and 60, which are held against the shoulders 66 and 68, I make the opening 70 somewhat wider than necessary to accommodate the prong members 42 and 44 and in alignment with the locking catch 58 immediately thereunder I provide another opening 90.

Thus a double pronged tool may be inserted in the openings 70 and 90 whereupon the locking catches 58 and 60 will be forced from under the shoulders 66 and 68 out of engagement therewith to thereby permit the cap 12 to be separated from the skirt 14.

If desired the lower end of the skirt 14 may be threaded as at 92 in order that a lamp shade or the like may be mounted on the socket.

Referring now to Figs. 7, 8 and 9, I have there illustrated a lamp socket according to my invention in which a different and novel switch means of the push pull type is used. It will be unnecessary to describe the construction of the socket as it is the same as that just described, with reference to Figs. 1 to 6, it being necessary only to direct attention to the change in the switch means.

The switch is illustrated in the off position in Fig. 8 with the resilient arm 76 tensioned away from the prong member 40 and so out of engagement with it. To close the switch the sliding member 94, at each end of which is a button 96 and 98, is pushed into the skirt 14 so that the button 96 is against the skirt and the button 98 away from the skirt.

The skirt 14 is recessed at 100 and opened at each side to accommodate the sliding member 94.

Extending from one side of the sliding member 94 I provide the rounded or curved contact member 102, made from a non-conducting material, which is brought into engagement with the resilient arm 76 to force it into contact with the prong element 40 and so close the switch.

In order to limit the off and on positions of the sliding member 94, I provide on the other side thereof the notches 104 and 106, in which the beveled end of the spring 108 is brought home by its tension when a notch is positioned thereat. Thus when the sliding member 94 is pushed into the closed position the notch 106 is freed of the beveled end of the spring 108, which permits the member 94 to slide along it until the beveled end is brought home into the notch 104 thereby fixing the switch on position. To open the switch the sliding member is pushed in the opposite direction whereupon the beveled end of the spring leaves the notch 104 and is brought home in the notch 106, the contact member 102 concurrently being brought out of engagement with the resilient arm 76 which springs away from the prong member 40 to open the circuit.

In order to retain the sliding member 94 against movement toward and away from the cap 12, I provide a slot in the member 94 in which the T member 110 is positioned with the head 112 resting on the sliding member. The ledge or wall 114 is provided with the recess 116 in which the T member 110 may be reciprocated and which also acts as a stop limit to fix the on and off switch positions.

The member 94 may be made from any suitable material such as metal, fiber or plastic of any suitable shape as round, square or rectangular in cross section, with one or both ends molded on the push button or threaded and screwed thereon.

Referring now to Figs. 10 to 12, I have there illustrated a socket according to my invention

which may be used with a special lamp such as the General Electric "Three-Lite" lamp. Such a lamp is composed of two filaments and internally wired so that current passing through one filament will provide a 50 watt light, current passing through another filament will provide a 100 watt light and current concurrently passing through both filaments will provide a 150 watt lamp. Of course other sizes of lamps may be used to provide a lamp having three different intensities that correspond to the particular filaments provided.

The switch by means of which either one of the filaments or both are connected in the circuit is conventional and only so much thereof as is required for an understanding of the construction required to modify it in accordance with my invention need be illustrated and described.

The socket illustrated in Figs. 11 to 12 comprises the cap 12, which frictionally fits on the skirt 14. Secured to the cap as by the screws 34 and 36, I provide the prongs formed by the resilient prong elements 38 and 40 and the prong elements 42 and 44. These prong elements have the extending locking catches 58 and 60, which engage the shoulders 66 and 68. The wires 46 and 48 comprising the cable 21 are inserted between the elements forming each prong. These elements of construction are the same as those described and illustrated with reference to Figs. 3 and 6.

Extending down from the washer 26, which separates the compartment 30 from the compartment 32, I provide the outer semi-circular contact 118, which is internally connected with one filament in the lamp, for example the 50 watt filament and internally of the lamp to the metallic base wall thereof which contacts prong 42 and 44 when the lamp is threadedly inserted in the skirt 14.

On the wall 28 at the center thereof is provided another circular contact 120 which is connected to one side of the other filament, for example the 100 watt filament, and internally to the metallic base wall of the lamp that contacts the prong 42 and 44.

Mounted in the switch member I provide the carrying plate 122, formed of a non-conducting material on which is riveted the switch support 124 in which the switch shaft 126 is journaled.

Mounted on the other side of the plate 122, I provide the corresponding and recessed member 128 in which the four-leafed switch contact member 130 may be rotated by the shaft 126. Extending from one side of the recessed member 128, I provide the terminal 134 which is mounted on the resilient bent over switch contact member 136.

Extending up from the center of the recessed member 128, I provide the terminal 138 which is secured to the resilient bent over switch contact 140 and at the other side of the recessed member I provide the terminal 142 which is secured to the resilient bent over switch contact 144.

The other switch terminals are provided on three of the leaves of the four-leafed member 130, the leaf 146, by means of which the switch is opened not having a contact and the leaf 148 having the contact 150, the leaf 152 having the contact 154, the leaf 156 having the contact 158.

On the obverse face of the four-leafed member 130 (as illustrated in Fig. 12) the contacts 150, 154 and 158 are electrically connected by a conducting ring secured to the member 130.

Thus in the position illustrated in Fig. 12, a 75 wall dividing the said sleeve into two compart-

circuit is made through the wire 46, the prong 38 and 40, terminal 134, switch contacts 136 and 150, the corresponding filament, the terminal 138, switch contacts 140 and 158, contact 120, the metallic base wall of the lamp and the prong 42 and 44 to the wire 48. The other filament is illuminated in the same way except that one side of the circuit is made through the wall of the lamp and the semi-circular contact 118 and contacts 144 and 156.

The four-leafed member 130 is rotated to the next position in the direction of the arrow 162, which brings the leaf 146 into engagement with the contact 136 thereby opening the circuit through the lamp. The next rotation in the direction of the arrow brings the contact 158 into engagement with the contact 136 to close the switch. Since this brings the leaf 146 into contact with the switch terminal 140 current through one of the filaments is opened but since the contact 136 engages the terminal 144 a circuit is completed through the other filament. Rotation to the next position brings the leaf 146 into engagement with the terminal 144 to open the circuit through this other filament and since the contacts 158 and 140 and contacts 154 and 136 are in engagement, the circuit through the first filament is concurrently closed. Further rotation to the next position will close the circuits through both filaments as heretofore described.

It will thus be seen that I have provided a socket having a three-way switch which can be readily assembled without the requirement of comparatively skilled labor and which has a minimum of fastening elements as distinguished from sockets of the prior art in which three-way lamps were utilized.

While I have described specific details illustrating embodiments of my invention, it will be understood that other modifications will now occur to those skilled in the art without departing from the spirit and scope of my invention.

I claim:

1. In an electrical socket for the threaded reception therein of a lamp, a sleeve, a cap member detachably mounted on the sleeve, a pair of spaced prongs extending from the cap and received in the sleeve upon mounting the cap thereon, a resilient catch member projecting from each prong, a shoulder for each prong arranged in the sleeve to engage a catch upon mounting the cap on the sleeve, the walls of said sleeve engaging the resilient catch member to urge the catch member away therefrom upon mounting the cap on the sleeve whereby the catch member is passed beyond the shoulder for said prong to be engaged thereby to engage it and prevent removal of the sleeve from the cap and switch means in the sleeve for electrically connecting the prongs to a lamp received in the socket.

2. In an electrical socket, a sleeve, a cap member detachably mounted on the sleeve, a pair of spaced prongs extending from the cap and received in the sleeve upon mounting the cap member thereon, a resilient member projecting from each prong, a shoulder for each prong arranged in the sleeve to engage a resilient member upon mounting the cap on the sleeve whereby the catch member is passed beyond the shoulder for said prong to be engaged thereby, the walls of said sleeve engaging the resilient members to urge the members away therefrom upon mounting the cap on the sleeve to engage it and prevent removal of the cap from the sleeve, a

ments and switch means cooperating with one of the prongs and arranged in one of the compartments, said wall having an opening under a resilient member and the shoulder.

3. In an electrical socket, a threaded sleeve, a cap mounted thereon, a pair of spaced prongs, and a switch means comprising a push pull member, a resilient contact member normally out of engagement with one of the prongs, an element on the push pull member for moving the resilient contact member against the said prong upon moving the push pull member into the socket, a pair of spaced notches on the push pull member and a spring means for entering one of the notches upon moving the push pull member in the socket and for entering the other notch upon moving the push-pull member out of the socket.

4. In an electric socket comprising a sleeve and a cap mounted thereon and a pair of spaced prongs received in the sleeve, a switch means comprising a member movable inwardly and outwardly of the socket, a resilient contact member adjacent one of the prongs and normally out of engagement therewith, an element on the movable member for moving the contact member against the adjacent prong upon moving the movable member inwardly of the socket and a spring means in engagement with the movable member, said movable member having spaced notches for receiving therein the spring means.

5. In an electric socket for threaded reception therein of a lamp, a cap member having a recess at one end thereof and an opening extending from the recess to the top thereof for receiving therein two wires, a prong extending from the cap for securing therein one of the wires,

8
a resilient catch extending from the prong, a second prong spaced from the first prong and extending from the cap for securing thereto the other wire, said prong having a second resilient catch extending therefrom, a sleeve received in the cap member in the recess thereof and frictionally held therein by the cap member, said sleeve having openings therein for receiving the prongs in the interior of the sleeve upon inserting the sleeve in the cap in the recess therein, walls of said sleeve at the said openings being undercut to provide shoulders extending away from the openings, the walls on the interior of the sleeve moving the resilient catches inwardly away therefrom upon insertion of the sleeve in the cap whereby the prongs are received in the openings said shoulders passed by the resilient catches to thereby release the catches by the walls of the sleeve to pass under the shoulders, said shoulders cooperating with the catches to prevent removal of the sleeve from the cap.
